RAZOR

Chao-Hsing Chu, Highland Park, Mich.

Application May 10, 1939, Serial No. 272,846

13 Claims. (Cl. 30—47)

The invention relates to new and useful improvements in razors, and more particularly to novel and useful improvements in an encased magazine razor openable for use and completely collapsible into and contained within its casing when not in use.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1—A is a perspective of the casing with the parts enclosed within the casing;

Fig. 1—B is a similar view showing the opposite side of the casing;

Fig. 2 is a perspective of the razor ready for shaving, and showing in dotted line positions the razor blade carrier and its support withdrawn from the casing, and in like manner on the other side the blade magazine withdrawn from the casing;

Fig. 3 is a detached perspective of the razor blade;

Fig. 4 is a detached perspective of the razor blade carrier;

Fig. 5 is a detached perspective of the withdrawable support on which the razor blade carrier is mounted;

Fig. 6 is a perspective of the casing with all the interior parts removed;

Fig. 7 is an enlarged perspective of the inner frame, removed from the casing, whereon the various movable parts are mounted;

Fig. 8 is a detached perspective of the blade magazine;

Fig. 9 is a detached perspective of a part of the handle;

Fig. 10 is a like view of the remainder of the handle;

Fig. 11 is a perspective of the closed casing of a simplified embodiment of the invention;

Fig. 12 is a similar view of the opposite side of the casing of Fig. 11, showing the handle partly open;

Fig. 13 is an elevation, partly diagrammatic, of the razor open and ready to shave;

Fig. 14 is a similar view of the closed razor;

Fig. 15 is a detached perspective of the inner frame, removed from the casing, on which the blade carrier is slidably mounted;

Fig. 16 is a perspective detail of the blade carrier;

Fig. 17 is a perspective detail of the handle with the parts separated for clearness; and

Fig. 18 is a perspective of the half casing showing the blade storage compartment.

Objects of the invention are to provide a very compact shaving utensil comprising a casing which when closed includes the blade and handle in a smooth compact envelope, these being simply and readily movable and projectable into shaving position and in like manner retractable again within the casing; to provide such a casing so shaped and disposed in connection with the projected razor blade to form a support and guide coacting with the face of the user while shaving; to provide such a device wherein movement of the handle from retracted position to operating or shaving position will automatically project the razor from within the casing out to shaving position, the reverse movement of the handle automatically retracting the blade into the casing, leaving the exterior of the casing closed and smooth; to provide a support for the blade carrier whereby it may be presented outside the casing, as for cleaning, and then restored into its usual position within the casing; to provide also within the casing a storage for blades, which is preferably a container slidable into and retractable from the casing, and having detent means for holding the handle in its stored position within the casing.

Referring now in detail to the embodiment of the invention illustrated by way of example in the accompanying drawings, a casing 1 is provided, preferably of relatively flat and elongate form and also preferably of rounded, flat cross-section. Disposed longitudinally along one of the narrow sides of the casing is an elongated slot 1^a extending substantially the full length of the casing, and through this slot a blade carrier 2 is projectable from the casing into shaving position and is retractable into the casing for storage. The blade carrier 2 is of general plate-like form, as shown in Fig. 4, and along its front side it has a seat 2^a for a razor blade 5, the blade fitting within the seat. At its front edge the carrier 2 has a longitudinally-disposed turned over lip 2^b, which on which are formed guards or stops 3, which

engage with the front edge of the blade to position it, and they also act as guards while shaving. A back stop 12 extends along the rear of the blade seat and the back edge of the blade fits against it. The blade 5 has a central aperture 5^a adapted to fit over a positioning lug 4 which extends upwardly from the blade seat 2^a. Means are provided whereby movement of the handle between its storage position and its operating position automatically projects the blade carrier and blade for shaving, and retracts them for storage, and comprises a cam slot 13 formed in the rear part of the blade carrier 2, the parts co-operating therewith being later described.

In accordance with one feature of the invention, the blade carrier may be moved outside of the casing, as for instance, for thorough cleaning although, so far as concerns the broader aspects of the invention, this feature may be omitted. Means to that end are included in the present embodiment, comprising a support for blade carrier which is insertable into and slideable in and out of the casing at one end thereof, but preferably not detachable, and the blade carrier, as embodied, is carried in and out with this support, and also is slideable on this support during its movement between storage position and shaving position. As embodied, a plate 6^a is slideable into and out of the casing through a transversely-extending slot 22 formed in a flat end 22^a of the casing 1. Said supporting plate 6^a is slideably supported in the general inner frame 23 (Fig. 7) which is mounted in fixed position within the casing 1. For this purpose frame 23 has a plate 25 extending both along and across substantially centrally of the casing 1. In plate 25 are formed longitudinally-disposed, recessed guiding grooves 26 into which fit corresponding longitudinally-disposed, projecting guides 15, formed on the underside of the support 6^a, whereby by the support is slideable on frame plate 25 into and out of the casing. On the outer end of the support 6^a is a finished plate 6 which fills the slot 22 in the closed position. If this support be dispensed with, the casing may be openable and the blade carrier be lifted out and reinserted.

The mounting for the blade carrier to permit the transverse movement thereof upon the support 6^a between shaving and stored positions comprises turned-over guideways 17 formed at either end of the plate 6^a, within which the ends of the plate 2 slide transversely. Lugs 16 are formed at the inner end of the plate 6^a to prevent total withdrawal thereof from the casing 1. A longitudinally-disposed slot 14 is formed in the plate 6^a to permit the handle 8 to connect with slot 13 in blade support 2 to effect the projecting and retracting movement of the blade carrier.

Referring now to the storable and withdrawable handle mechanism, a longitudinal slot 20 is disposed along one of the broad sides of the casing 1, and a corresponding slot 20^a is formed in the frame 23. A hollow handle 8, of rectangular cross-section has a rounded head 8^a, from which projects at either side cylindrical pins 35, which pins are adapted to slide along guideways 28, formed at either side along the edges of the slot 20^a. Located centrally along the guideways 28 are two projecting tongues 29, and in the pins 35 are formed recesses 36. When the handle 8 is swung out from storage position in slot 20 to the perpendicular position, as shown in Fig. 2, and is slid along the guideways 28, the tongues 29 will enter the apertures 36 and centrally position the handle in the perpendicular position, and

hold it there for shaving and until the handle is slid backwardly along the guides 28 preparatory to being swung down into storage position.

The embodied means whereby the handle during its movement from storage to operative position automatically projects the blade carrier 2 comprises a pin 33 projecting from the hub 8^a of the handle, and as the handle is brought from the storage position to the perpendicular operating position, the pin 33 passes through a slot 30 in plate 25, through slot 14 in the supporting plate 6^a, and engages with the curved cam slot 13 in blade carrier 2, and during the sliding movement of the handle 8 along the guideways 28 until stopped position by the tongues 29, the blade carrier is projected by the action of pin 33 sliding in slot 13 to the shaving position as shown in Fig. 2. Upon the reverse movement of the handle back to storage position, the blade carrier is retracted in like manner. The handle is extensible for shaving and contractable for storage and to this end comprises a rectangular hollow outer member 9 which is free to slide on member 8. The member 8 has a slot 11 in the side thereof, and the member 9 has a projection 10 extending into slot 11, which serves as a stop. For the purpose of holding the handle in the storage position, the handle member 8 has an apertured end 37 with which engages a detent stop 31.

In accordance with one feature of the invention, storage for a supply of new blades is provided within the casing, and as shown, a space 24 is provided within the frame 23 for that purpose. Preferably a blade container or magazine 32 is utilized as a carrier for the blades, the carrier being slideable into and out of the space 24. A slot 19 is formed in the flat end 22^b of the casing 1, through which the blade magazine 32 is slideable into and out of the space 24. The carrier 32 is provided with an end plate 7 which in the closed position abuts against the end plate 22^b of the casing. In this form the handle detent 31 is conveniently mounted on the plate 7, and projects through a slot 18 into the interior of the frame to engage with the hollow end 37 of the handle member 8 as it lies within the slot 20^a, thereby holding the handle in the stored or closed position. When in this closed position a lug 34 on the hub 8^a of the handle extends through slots 30 and 14 into slot 13, and holds the parts locked in stored position.

In Figs. 11 to 18 is shown another embodiment having simpler mechanism and of considerably less size. In this embodiment the endwise-slidable carrier for the transversely-movable blade support is dispensed with, and the casing is openable for the purposes of cleansing and blade-changing, and the form of other parts is modified to suit the different construction. The same reference numerals are applied to the same parts. In the present embodiment of this compact and simplified form, the casing 1 comprises two longitudinal halves 1^b and 1^c which are openable along a hinge 40, and are held firmly closed by spring snap fingers 1^d. The transversely-movable blade carrier 2, which is projectable and retractable by the pivotal and slideable movement of the handle 8, 9, as previously shown and described, is mounted directly upon the plate-like frame member 25^a, and the guideways 17 in which the blade support moves transversely are formed on either end of this frame plate 25^a, the blade support being mounted directly upon and slideable over plate 25^a, the blade carrier 2 being projectable from and retractable into the slot 1^a.

The handle is the same or substantially similar to that previously shown and described, and operates in the same manner to project and retract the blade support and to fold into the casing, being held in the casing by a friction or snap fit. In this case when the handle is rocked, the pin 33 passes through the slot 14 in the frame plate 25^a and engages with the slot 13 to move the blade support during the sliding action of the handle to the central position which it occupies for shaving. As shown in Fig. 17, in this embodiment the head of handle 8 is provided with the flat extensions 35^a which are adapted to revolve in circular recesses 37 adjacent one end of the frame member 25^a when the handle is to be moved from the recessed position, and to slide along groove 38 when the handle is moved to the central portion of the casing 1 which is the shaving position.

Ample blade storage is provided within one part of the casing, as shown in Fig. 18. Pivoted on the hinge pin 40 is a flat plate 41 of approximately the area of the inner face of the half casing, and integral with or joined to the ends of plate 41 are two segmental plates 42 and 43 of approximately the shape and size of the end plates of the half casing. A snap fastening 44 may be provided to hold the parts closed. The blades are stored within this space and are accessible when it is opened as shown in Fig. 18.

This form presents a complete and very small and compact collapsible razor, with all the parts connected together, without separate or detached parts that must be screwed together and unscrewed or otherwise fastened and unfastened, which is simply and readily openable for cleansing and blade-changing without removal and replacement of detachable parts, and which has ample blade storage.

The invention in its broader aspects is not limited to the specific mechanisms shown and described but departures may be made therefrom within the scope of the accompanying claims without departing from the principles of the invention and without sacrificing its chief advantages.

What I claim is:

1. A razor comprising a casing of flat rounded cross-section, said casing having a longitudinal slot extending along one of its thinner sides, and a second longitudinal slot extending along one of its broader sides, a blade carrier mounted within the casing and movable outwardly through said first-mentioned slot to present the blade in shaving position, a handle mounted within the casing and movable to lie within said second slot flush with the casing and with its ends lying within the borders of the casing and movable to be turned out perpendicularly for shaving, and connections between said handle and blade carrier for projecting the carrier from its slot and for retracting it within the casing by longitudinal movement of said handle along the second slot.

2. A razor comprising a casing of flat rounded cross-section, said casing having a longitudinal slot extending along one of its thinner sides, and a second longitudinal slot extending along one of its broader sides, a blade carrier mounted within the casing and movable outwardly through said first-mentioned slot to present the blade in shaving position, a handle mounted within the casing and having swinging and longitudinally sliding movement to lie within said second slot wholly within the outline of the casing and to be swung outwardly perpendicular to the casing and to be slid longitudinally along the second slot, and

connections between said handle and blade carrier for projecting the carrier from its slot and for retracting it within the casing.

3. A razor comprising a casing having a pair of slots extending longitudinally thereof, a blade carrier mounted within the casing, a handle pivotally and slidably mounted on the casing in one of said slots to have pivotal and longitudinally slideable movement between shaving position and storage position and means operated by the movement of the handle between said positions for projecting the blade carrier from the other slot for shaving and for retracting it for storage said handle in storage position being wholly within the outline of the casing.

4. A razor comprising a casing of flat rounded cross-section having a slot extending longitudinally of one of the thin sides of the casing, a blade carrier mounted within the casing, and projectable through said slot to a shaving position and retractable within the casing for storage, a handle mounted on a flat side of the casing to have pivotal and longitudinally slideable movement between shaving position and storage position at the flat side of the casing and means operated by the movement of the handle between said positions for projecting the blade carrier from the slot for shaving and for retracting it for storage the ends of the handle in storage position being within the outline of the casing.

5. A razor comprising a casing of elliptical cross section, said casing having a longitudinal slot extending along one of its thinner sides and a second longitudinal slot extending along one of its broader sides, a handle normally positioned within the second slot and having one end pivotally and slidably secured within said second slot, a blade carrier movably mounted within the casing, and means connecting the carrier and the handle and carried by the handle to operatively engage the carrier to protrude the carrier through the first slot when the handle is slid along the second slot in an upright position.

6. A razor comprising a casing of elliptical cross section, said casing having a longitudinal slot extending along one of its thinner sides and a second longitudinal slot extending along one of its broader sides, a handle having one end pivotally secured in the second slot and longitudinally slideable therein, a blade carrier movably mounted within the casing, and means connecting the blade carrier and the handle when the handle is in an upright position with respect to said casing to protrude the carrier through the first slot when the handle is slid longitudinally along the second slot.

7. A razor comprising a casing having a pair of slots along the length thereof, a blade carrier movably mounted within the casing, a handle connected to the casing and longitudinally slideable along one of the slots, and means connecting the handle and the blade carrier for protruding the carrier when the handle is in an upright position with respect to said casing through the other slot when the handle is slid longitudinally to a position in its slot substantially equidistant from the ends of the casing.

8. A razor comprising a casing having a pair of longitudinal slots therein, a blade carrier movably mounted within the casing, a handle having one end secured within the casing for longitudinally slideable movement, said handle extending out of the casing through one of the slots, and means for connecting the blade carrier and the handle when the handle is in an up-

right position with respect to said casing to cause the blade carrier to protrude from the other slot when the handle is moved longitudinally along its slot from a position adjacent one end of the casing to a position substantially equidistant from the ends of said casing.

9. A razor comprising a casing having a pair of longitudinal slots therein, a blade carrier movably mounted within the casing, a handle normally lying within one of the slots, said handle being pivotally and slidably secured at one end thereof to the casing to be swung out from the casing and slid lengthwise of the slot, and means for connecting the blade carrier and the handle to protrude the blade carrier from the other slot when the handle is slid along its slot from a position adjacent one end of the casing to a position substantially equidistant between the ends of said casing.

10. A razor comprising a casing having a pair of longitudinal slots therein, a blade carrier movably mounted within the casing, a handle normally lying within one of the slots, said handle being pivotally and slidably secured at one end thereof to the casing to be swung out of the slot and slid therealong, and means on the end of the handle operable to engage the blade carrier when the handle is swung out of its slot and to protrude the blade carrier through the other slot as the handle is slid along its slot from a position adjacent one end of the casing to a position substantially equidistant from the ends of the casing.

11. A razor comprising a casing of elliptical cross section having a pair of longitudinal slots therein and a third slot in one of the end walls thereof, a plate movably mounted within the casing to be slid out of the casing through the slot in the end wall, a blade carrier movably mounted on the plate, a handle normally lying within one of the longitudinal slots, said handle being pivotally and slidably secured at one end thereof to the casing to be swung out of the slot and slid therealong, and means for connecting the handle

and the blade carrier to protrude the blade carrier through the other longitudinal slot as the handle is slid along its longitudinal slot from a position adjacent one end of the casing to a position substantially equidistant between the ends of the casing.

12. A razor comprising a casing of elliptical cross section constructed in two halves hingedly attached together along one of the thinner sides of the casing, said casing having a longitudinal slot along the broader side of the lower half thereof and a second longitudinal slot along the thinner side opposite the hinged thinner side, a blade carrier movably mounted within the casing on the lower half thereof, a handle normally lying within the slot along the broader side, said handle being pivotally and slidably secured at one end thereof to the lower half of the casing to be swung out of said slot and slid therealong, and means for connecting the handle and the blade carrier to protrude the blade carrier through the longitudinal slot along the thinner side as the handle is slid along its slot from a position adjacent one end of the casing to a position substantially equidistant between the ends of the casing.

13. A razor comprising a casing of elliptical cross section having a pair of longitudinal slots therein, a blade carrier movably mounted within the casing and having a substantially S shaped groove in one surface thereof, a handle normally lying wholly within the outline of the casing in one of the longitudinal slots, said handle being pivotally and slidably secured at one end thereof to the casing to be swung out of the slot and slid therealong, and a pin mounted on the end of the handle operable to engage the blade carrier in the groove when the handle is swung out of its slot and to protrude the carrier through the other slot as the handle is slid in its slot from a point adjacent one end of the casing to a point substantially equidistant from the ends of the casing.

CHAO-HSING CHU.
